BAGSAR PASHIGIAN, OF HAVERHILL, MASSACHUSETTS, AND HUBERT J. GALLANT,
OF EXETER, NEW HAMPSHIRE.

ATTACHMENT FOR UTILIZING SHOE-SEWING MACHINES TO STICK A COLD-PROCESS
TAPE ON SHOES TO REENFORCE SAME.

Application filed July 27, 1927. Serial No. 208,775.

The purpose of our invention is to provide a novel attachment for shoe sewing machines whereby a cold process tape may be pressed or hammered onto the uppers of shoes to 5 serve as a reenforcing element.

We attain these and other objects of our invention by the mechanism illustrated in the accompanying drawings, in which—

Figure 1 is a side elevation of a sewing 10 machine using our attachment;

Fig. 2 is an end elevation of same;

Fig. 3 is a top plan view of the upper 15 tape guide;

Fig. 4 is a longitudinal view on line 4—4 of Fig. 3;

Fig. 5 is an end elevation of the presser 20 foot tape guide;

Fig. 6 is a vertical section on line 6—6 of Fig. 5: and

Fig. 7 is a horizontal section on line 7—7 of Fig. 5 showing the presser foot tape guide in top plan.

Like numerals designate like parts 25 throughout the several views.

Referring to the accompanying drawings we utilize a conventional shoe sewing machine 1 such as the Singer sewing machine having a tape reel standard 2 carrying the tape reel 3 from which the tape 4 is unwound and drawn through the bifurcated end or slit 9 of the upper tape guide 5. Member 5 has an enlarged shank 6 which is fastened to the reciprocating rod 8 of the sewing machine by suitable means such as the set screws 7. The tape 4 passes over a roller or other suitable antifriction surface 10 and between a 35 downwardly extending lip 18 and the sharpened edge 12 of a flat finger 11. Finger 11 is mounted on the wire 13 the bent end 14 of which is provided with an eye 15 to which a spring 16 is attached which spring in turn is secured to a hook or eye 17 fastened to the upper tape guide 5 as shown in Figs. 3 and 4.

The spring 16 engaging the end of wire 14 and actuating wire 13 and finger 11 causes the edge of the latter to contact against the surface of the tape 4 to keep it from rolling or curling, as shown in Fig. 4.

Referring to Figs. 5, 6 and 7, we provide 50 a presser foot 19 the shank 20 of which is affixed to the reciprocating rod 23 of the sewing machine by suitable means such as the metal strap or collar 20 and screw 22. The

foot portion 24 of presser foot 19 is provided with a channel or cut-out portion 25.

We provide a tape guide 26 which has a narrow channel 27 extending through it and through which the tape 4 passes before coming in contact with the leather or other material 31 on which it is to be pressed and thereby stuck. The tape guide 26 is provided with laterally extending arm 28 which is fastened by screw 29 and a stud 30 carried by the presser foot engaging a corresponding opening in the end of the arm 28, as shown in Fig. 7.

This attachment is used to fasten or stick a cold process tape on shoes to serve as a reinforcement on the uppers of shoes. Tape guide arm 5 is placed on a bar which reciprocates up and down as the machine operates. The tape first unwinds from its reel or spool and passes through the narrow slot or opening at the bifurcated end of the upper tape guide arm pulling the tape down by its force 75 through the guide and then through the lower guide 26 and under the presser foot 24 thus sticking the tape on the uppers of the shoes, by means of the blows or pressure exerted by the presser foot against the outer 80 surface of the tape. The inner surface of the tape of course carries an adhesive substance.

What we claim is—

1. As a new article of manufacture for a machine of the type described, a device for 85 guiding tape comprising an arm, means for fastening the shank of the arm to the reciprocating rod of a sewing machine, the arm having its free end bifurcated, and having a downwardly extending lip, and a flat finger 90 mounted between the bifurcated portions of the end, a wire to which the finger is fastened, a spring fastened to the wire, and means for securing the spring to the tape guide arm, whereby the finger will resiliently engage a 95 strip of tape as it passes between the bifurcated portions of the arm to keep the tape smooth.

2. As a new article of manufacture for a machine of the type described, a device for 100 guiding tape comprising an arm, means for fastening the shank of the arm to the reciprocating rod of a sewing machine, the arm having its free end bifurcated, and having a downwardly extending lip, a flat finger 105 mounted between the bifurcated portions of

the end, a wire to which the finger is fastened, a spring fastened to the wire, means for securing the spring to the tape guide arm, whereby the finger will resiliently engage a strip of tape as it passes between the bifurcated portions of the arm to keep the tape smooth, and an anti-friction roller over which the tape is guided.

3. An attachment for a shoe sewing machine, consisting of an upper tape guide affixed to the reciprocating rod of the sewing machine, said guide having a downwardly extending lip at its free end and having a flat

finger resiliently held in contact with the lip and between which elements the tape passes, and a presser foot affixed to the lower end of the reciprocating rod of the sewing machine, said presser foot having a tape guide having a substantially vertical channel through which the tape is guided before it contacts with the material to which it is engaged by the force of blows delivered on it by the foot portion of the presser foot, substantially as described.

BAGSAR PASHIGIAN.
